Specification for Design.

Patented Oct. 14, 1919.

Application filed April 2, 1919. Serial No. 287,077. Term of patent 3½ years.

To all whom it may concern:

Be it known that I, JOHN FLYNN, a citizen of the United States, and resident of Akron, Summit county, Ohio, have invented a new, ornamental, and original Design for a Vehicle-Tire, of which the following is a specification, reference being made to the accompanying drawings, forming a part thereof.

In the drawing,

Figure 1 is a plan view of a portion of a tire, flattened out, and

Fig. 2 is a sectional view on line 2—2 of Fig. 1.

I claim:

The ornamental design for a vehicle tire as shown.

JOHN FLYNN.
